UNITED STATES PATENT OFFICE

114,920

DESIGN FOR AN ASHTRAY OR SIMILAR ARTICLE

Herbert Gordon Dyke, New York, N. Y.

Application March 11, 1939, Serial No. 83,519

Term of patent 7 years

To all whom it may concern:

Be it known that I, Herbert Gordon Dyke, a citizen of the United States and a resident of the Borough of Manhattan, city, county, and State of New York, have invented a new, original, and ornamental Design for an Ashtray or Similar Article, of which the following is a specification, reference being had to the accompanying drawing forming a part thereof.

Fig. 1 is a perspective view of an ashtray embodying my design;

Fig. 2 is a plan view thereof;

Fig. 3 is an end view thereof; and

Fig. 4 is a side view thereof.

I claim:

The ornamental design for an ashtray or similar article, substantially as shown.

HERBERT GORDON DYKE.
